BRACELET CONNECTER

James Walter Greenbowe, Newark, N. J., assignor
to Bruner-Ritter, Inc., a corporation of New
York

Application March 5, 1935, Serial No. 10,138

9 Claims. (Cl. 24—71)

This invention relates to wrist watch straps and more particularly to the extensible connectors used in conjunction with such straps.

An object of the invention is to provide a connector which is rugged and easily operated.

A further object of my invention is to provide a connector of the foldable link type having a take-up for the slight slack in the strap to which it is attached when on the arm of the wearer, the take-up being automatically released for resetting upon unfolding the links by a positive action upon the take-up mechanism.

A still further object of the invention is to provide a foldable link type connector with a ratchet and pawl take-up, the pawl being disengaged from its ratchet by a lateral movement automatically performed when the links are substantially completely unfolded.

A specific object of the invention is to provide a ratchet and pawl mechanism for the take-up of a bracelet connector which is automatically actuated through a lateral camming action upon unfolding the connector to disengage the ratchet and pawl mechanism.

Other objects of the invention will become apparent from the following description when taken in conjunction with accompanying drawings, in which,

Fig. 1 is a top plan view of the bracelet connector in folded position.

Fig. 2 is a view similar to Fig. 1 but looking at the connector from the underneath side.

Fig. 3 is a side elevational view showing the connector in folded position and in dotted outline the connector when partially opened.

Fig. 4 is a plan view of the connector with the cam plate removed to show the internal take-up mechanism.

Fig. 5 is a fragmentary plan view showing the manual operation of the release for the take-up.

Fig. 6 is a cross-sectional view taken on the line VI—VI of Fig. 4.

Fig. 7 is a fragmentary cross-sectional detail view of the cam and lever release for the take-up taken on line VII—VII of Fig. 4.

Fig. 8 is a cross-sectional view taken on line VIII—VIII of Fig. 4.

Fig. 9 is a plan view similar to Fig. 4 but illustrating a further modification.

Fig. 10 is a plan view similar to Figs. 4 and 9 illustrating a still further modification.

The present invention is directed to an improved form of wrist watch strap or bracelet connector in which a folding member is hinged to a housing containing mechanism to lock or release

an extension member, means being provided to normally lock the extension member and means movable laterally under the action of means associated with the pivot point of the folding member, operable when the folding member is moved a given distance to cause a lateral movement of a member for releasing the extension member.

One selected embodiment of the invention is shown in Figs. 1 to 8. As shown a connector element 10 may comprise a trough shaped housing 11 having side flanges 12 and 13. One end 14 of the housing is provided with bearings 15 and 16 to receive a pintle 17 as the pivot point for one end 18 of folding member 19 provided with a ferrule 21 movable about the pintle. The folding member 19 is pivotally connected at 22 to a folding member 23, the free end of which is connected to one section 24 of a chain which may be attached to one side of a wrist watch (not shown). The other side of the watch may be attached to one end of another section of chain 25. The other end of the chain 25 may connect with an extension member 26, slidably in the housing 11.

The extension member 26 is preferably in the form of a flat strip and in the construction illustrated includes guide strips 27 and 28 held by cross pieces 29 and an end bar 31 to which the section 25 is attached. The member 26 is proportioned to slide between flanges 12 and 13 and lugs 32 pressed from the flanges keep the member 26 in proper sliding relation to surfaces 33 of wall 34 of the housing 11 (see Fig. 6). The wall 34 is provided with a channel or recess 34' to receive a self-acting latch or dog 35 provided with a lip 36 engageable with teeth 37 carried on the inner edge of the strip 27 of the extension member 26. The latch 35 may include a resilient arm 38 extending from a shank 39 fastened by a clamp 41 which holds the latch member fast to the bottom wall of the housing.

The clamp also serves as a stop to limit the movement of the extension member 26. The latch normally acts to engage teeth 37 and thus hold the member 26 from movement outwardly from the housing. The inclined faces of the teeth are so arranged however that the extension member 26 may be moved inwardly for an adjustment to shorten or close the bracelet to make it more snugly fit the wrist when the folding members are closed and an adjustment is desired.

When the connector is closed and the bracelet is fitted to the wrist by adjusting the extension member 26 it may be desirable to readjust or release the said member to enlarge

the bracelet or strap. For this purpose a rocker member 42 is provided having a finger piece or projection 43 which extends outwardly from the housing. The member 42 is disposed in the channel or recess 34' and one practical form as shown in Figs. 4 and 5 may comprise a flat strip with arcuate edges 44 and 45 arranged to contact with the side walls of the channel 34' to permit the member 42 to rock with the arcuate surface as 10 the fulcrum.

The member 42 may have an arm 45 provided with a right angle notch 46 to receive an end 47 of the latch member 35. The latch member may be formed to firmly engage the end of the 15 arm 45 and the resilient arm 38 serves to hold the lip or tooth 36 engaged with one of the teeth 37 (see Fig. 5). When it is desired to release the teeth 37 the finger piece is moved laterally as shown and the member 42 is rocked 20 lifting the latch 35.

It will be understood that in the present type of connector the bracelet is always closed, that is, although the folding members may be open to permit the bracelet to be removed from or 25 slipped over the hand onto the wrist the closed circle construction is maintained.

With this construction it is necessary to provide for a complete opening of the bracelet so that it will easily pass over the hand and it is 30 therefore desirable to have the extension member automatically released when the connector is opened.

In the present construction this release is accomplished by utilizing a side thrust obtained by 35 a movement of the hinge ferrule 21 during the movement of the folding member or link 19. The ferrule may, as shown, be provided with a cut out portion so formed as to provide a helical surface or face 48 and the member 42 may be provided with a follower or lug 49. The latch member 40 normally holds the follower against the cam face 48 so that as the ferrule turns, the folding member is lifted. Considerable movement is possible since the folding member moves 180° 45 from a closed to an open position.

When the folding members are closed the latch is free to act since the arrangement of the cam surface 48 is such that when the folding member 19 is closed the cam surface is removed leaving 50 the member 42 free to be actuated by the finger piece 43. The folding members 19 and 23 when closed, lie one on the other and are held in closed 55 relation by extending retainer pieces 51 which extend inwardly from the flanges 11 and 12.

In Fig. 9 of the drawings a modified structure 55 is shown wherein a latch member 52 is provided with a resilient arm 53 having an end 54 loosely held by a retainer piece 55. The latch member is provided with a lip or tooth 56 to engage teeth 60 37 on the extension member 26, the construction of which is the same as shown in Fig. 4. The latch member 52 instead of being operated by means of a rocker member, is provided with a fulcrum point 57 and a lug 58 is engaged by the 65 cam face 48 so that when the folding member 19 is open the tooth 56 is lifted releasing the member 26. When the folding member 19 is closed the tooth 56 may be lifted by a lateral movement of a finger piece 59.

Fig. 10 shows a latch member 61 secured at one 70 end 62 by a clamp 41 and having a lug 63 engageable with a cam surface 64 formed in the ferrule of the member 19. The latch 61 is provided with a tooth 65 which normally engages teeth 75 37 of the member 26. It will be noted

that the cam surface 64 is opposite with respect to the cam surface 48 since the movement of the latch member 61 is direct, the movement being about a fulcrum point at the fixed end of the latch. A hand piece 66 is provided to cause a 5 movement of the latch to release the member 26 when the folding members are closed.

Although the present invention provides a connector of the closed ring type it is obvious that the several operating elements utilizing the action of a cam or force member moved under the action of the moving hinge or ferrule may be employed in other constructions where the simplicity of operation attained by a lateral acting release of an extension member is desired. 10 15

A selected practical embodiment of the invention is shown and described but it is to be understood that modifications may be made there-in without departing from the spirit and scope of the invention as defined by the appended 20 25 claims.

What I claim is:

1. A connector for a wrist watch strap comprising a housing, a folding member pivotally connected to one end of said housing, an extension member slidable in said housing, teeth on said extension member, a latch member in said housing for engaging said teeth, and means mounted at the pivot of said folding member for moving said latch member laterally to disengage said teeth. 25 30

2. A connector for a wrist watch strap comprising a housing, a folding member pivotally connected to one end of said housing, an extension member slidable in said housing, teeth on said extension member, a latch member in said housing for engaging said teeth, a rocker member in said housing having an arm engaging said latch member and means carried at the pivot of said folding member for operating said arm 35 40 to rock the same and lift said latch member.

3. A connector for a wrist watch strap comprising a housing, a foldable member, a pintle at one end of said housing, a ferrule at one end of said foldable member and movable about said pintle, an extension member slidable in said housing, a plurality of teeth on said extension member, a self-actuating latch in said housing for engaging said teeth, a helical cam surface on said ferrule and means connected with said 45 50 latch engaging with said cam surface to disengage said latch from said teeth.

4. A connector for a wrist watch strap comprising a housing, a folding member, a hinge including a pintle and a ferrule connecting said folding member to one end of said housing, an extension member having teeth slidable in said housing, a latch in said housing for engaging said teeth to hold said extension member in an adjusted position within said housing when said folding member is closed, a helical cam on said ferrule and means on said latch engaging said cam to cause said latch to be disengaged from said teeth upon a movement of said ferrule when said folding member is moved to an open position. 55 60 65

5. A connector for a wrist watch strap comprising a slide member, a folding member, a hinge for pivotally attaching said folding member to said slide member, a second slide member, 70 means for retaining said slide members in slidable relation, teeth on one slide member, a latch member on the other slide member, means for holding said latch member engaged with said teeth, a cam member carried by the hinge of 75

said folding member and means on said latch member engaging said cam for moving said latch member laterally to release said teeth.

6. A connector for a wrist watch strap comprising a slide member, a folding member, a hinge for pivotally attaching said folding member to said slide member, a second slide member, means for retaining said slide members in slidable relation, teeth on one slide member, a latch member on the other slide member, means for holding said latch member engaged with said teeth, a helical cam movable about the longitudinal axis of said hinge and means on said latch member engaging said cam for moving said latch member to release said teeth.

7. A connector for a wrist watch strap or the like comprising a slide member, a folding member, a hinge for pivotally attaching the folding member to the slide member, a second slide member, means for retaining said slide members in slidable relation, teeth on one of said slide members, a latch member on the other slide member, means for normally holding said latch member engaged with said teeth, and a lateral cam surface movable about said hinge and means on said latch member engaging said cam for moving said latch member from engagement with said teeth.

8. A connector for a wrist watch strap or the like comprising a slide member, a folding mem-

ber, a hinge for pivotally attaching the folding member to the slide member, a second slide member, means for retaining said slide members in slidable relation, teeth on one of said slide members, a latch member on the other slide member, means for normally holding said latch member engaged with said teeth, and a helical cam movable about the longitudinal axis of said hinge and means on said latch member engaging said cam for moving said latch from engagement with said teeth.

9. A connector for a wrist watch strap or the like comprising a slide member, a folding member, a hinge for pivotally attaching the folding member to the slide member, a second slide member, means for retaining said slide members in slidable relation, teeth on one of said slide members, a latch member on the other slide member, means for normally holding said latch member engaged with said teeth, a helical cam movable about the longitudinal axis of said hinge and means on said latch member engaging said cam for moving said latch member from engagement with said teeth when said folding member is open and means extending from said connector when closed for manually releasing said latch member from engagement with said teeth.

JAMES W. GREENBOWE. 30
